GOLF BALL CLEANER

Kenneth A. Roddy, 15322 E. Ritter Circle,
Houston, Tex. 77071

Filed Dec. 22, 1971, Ser. No. 211,144

Term of patent 14 years

Int. Cl. D7—05; D15—05
U.S. Cl. D49—1 A

FIG. 1 is an isometric view of the top and part of the elevational periphery of an embodiment of a golf ball cleaner, showing my new design; and

FIG. 2 is an isometric view of the top and part of the elevational periphery of another embodiment thereof.

The parts, not shown, of the elevational peripheries of the two embodiments are in correspondence with the parts shown.

I claim:

The ornamental design for a golf ball cleaner, as shown and described.
